UNITED STATES PATENT OFFICE

REINHOLD B. MARSCHKE, OF ST. PAUL, MINNESOTA

FOLDING STAIR

Application filed November 10, 1927. Serial No. 232,309.

My invention relates to folding stairs, the primary object of which is to provide a stair with a hanger means wherein the stair may be supported from the ceiling of a building 5 or from an upper level casing so that the stair may unfold to a floor below. The hanger being of a simple inexpensive construction yet having adjusting means and a shape such as to provide a most efficient 10 means of supporting and operating the stair.

A feature of the invention resides in providing a hanger arm which is easily adjustable as to length after it has been attached 15 in position and having a means for attaching the same on the ends thereof which permit of the adjustment by simply rotating the same either in a right or lefthand direction until the hanger arm is of the 20 proper length.

My invention includes a hanger having rod means which are adapted to form the supporting arms and which function with other rod means to slideably hold the members together and to permit them to function 25 in a practical manner. This includes pairs of rods which extend on either side of the stair which are adjustable as to length and other rods slideably engaging said pair of 30 rods which engage against a shoulder formed on said adjustable rod and which are connected with spring lever means for lifting and balancing the stair in folding, while the other rod means include a member 35 adapted to connect with a lower section and having a long slideable hook end which operates to cause the hanger arm to be rigid while the stair is open, merely by holding the stairs to the floor and keeping it from 40 vibrating.

These objects, together with other details and features of the invention will be more fully and clearly set forth in the specification and claims.

45 In the drawings forming part of this specification:

Figure 1 is a perspective view of one side of the stair.

50 Figure 2 illustrates the stair folded in compact state.

Figure 3 illustrates one of the adjustable rod arms or hangers.

Figure 4 illustrates the attaching flange and nipple.

Figure 5 is a front view of the flange. 55

Figure 6 illustrates the other side view of my stair.

Figure 7 is a detail of one end of the stair when folded.

Figure 8 is a detail of the hanger arm. 60

Figure 9 is an edge view of the detail illustrated in Figure 8.

Figure 10 illustrates one of the lifting rods for the balancing springs.

Figure 11 illustrates the supporting rod 65 for the lower section.

My folding stair A is formed with an upper section 10, an intermediate section 11, and a lower section 12. The sections 10 and 11 are hinged together on top of the side 70 rails 13 by the hinges 14, while the sections 11 and 12 are hinged together by the hinge members 15 on the bottom of the rail.

On one side of the stair A I provide a hand rail B which is connected on the bottom to the bracket 16 which is attached near the hinging point 14. This bracket 16 is provided with a hinging point 17 so that the rail B may be permitted to assist in lifting the sections 11 and 12 over the center of the point of hinging in the hinges 14. The upper end of the hand rail B is connected to a spring operated arm 18 which is connected to the side rail 13 of the section 10 and this spring functions to have a tendency to pull upward on the rail B. The object of this spring is that as soon as the stair has started to fold with the section 11 folding over towards the section 10, the hand rail B assists in folding the stair. 80

One of the primary features of the invention resides in the hanger arms C which are adapted to support the main section 10 and connect the same with the casing D above the floor E. These supporting hangers C 95 are in the form of two rods 20 and 21 which have flattened ends adapted to overlap and be hinged together at 22. The rod 20 is formed with an enlarged portion 23, while the rod 21 carries an adjustable or slideable 100

collar 24. The collar 24 is provided with a set screw 25 for holding the same in set position. The ends 26 and 27 of the rods 20 and 21 respectively, are right and left hand threaded and are adapted to engage in the nipples 28 of the supporting flanges 29. The flange members 29 are in the form of collars having nipples rigidly attached thereto and the nipples are threaded so as to receive the right and left hand threaded ends 26 and 27 of the hanger rod C. The supporting flanges 29 are adapted to be attached to the side rails 13 of the section 10 on one end and to the side of the casing D on the other end.

I provide balancing and lifting springs F which are adapted to be attached to the toothed members 30 which adjustably engage the inner ends of the lifting springs 20 F, while the other ends 31 of the lifting spring are connected to the lifting rods 32. These lifting rods are each formed with a hook end 33 on one end and the other end is formed with an attaching end 34 which is attached to the free end of the arm 31. When the stair is extended as illustrated in Figures 1 and 6, then the hook end 33 of the rod 32 which is offset from the body of the rod is adapted to engage the shoulders 30 23 formed on the portions 20 of the hanger C.

I provide a rod arm 36 which is adapted to be pivotally connected at 37 in one of the side rails 13 opposite to the hand rail D 35 to the section 11 as illustrated in Figure 6. The other end of the arm 36 is formed with an elongated hook end 38 which hooks over the lower portion 21 of the hanger C and is adapted to be engaged by the collar 24 when 40 the stair is in extended position as illustrated in Figures 1 and 6.

The rods 32 and 36 have their hook ends 33 and 38 respectively, formed so that these rods can be easily hooked over the rods 20 45 and the rod 21 of the hanger C. This permits the stair A to be easily assembled and it is an important feature in the present hanger construction of my folding stair A.

The advantage of my present folding stair 50 A resides more particularly in the simple easily adjustable hanger arm C which may be turned in either direction to lengthen or shorten the same owing to the attachment of the ends by the lefthand threads and the shoulders 23 which function with the arms 32 to properly engage the rods of the hanger C. I provide a shoulder lug 39 on the hand rail B which engages against one of the hangers C when the stair is extended to steady 55 the same and I also provide the rod 36 for engaging against the adjustable collar 24 on the other hanger rod so that the hangers C are steadied on both sides when the stair 60 is in use. This provides the necessary means

of steadyng the hangers at each side of the stair A.

In a stair of this kind it is highly desirable to provide a means of assembly of the parts of a very simple nature. In this hanger means hereinbefore described I have provided such a construction with the parts so arranged and designed that they may be connected together and adjusted very quickly and easily so that stair A can be made up for a reasonable price and can be readily adjusted to function in a practical manner even when it is put together by the ordinary carpenter or individual in applying and using my stair. The easy adjustment of the hangers C make it more easy to set up my stair after it is received by the customer even though it is all assembled and ready to be applied in the casing or opening. These stairs are ordinarily sent out all assembled 70 as illustrated in Figure 2, nevertheless, owing to the different adaptations of the same it is possible that the hanger C may need adjustment when the stair is in operative position. This may be due to the position of the 75 floor or other connecting parts. Therefore I have found that the particular hanger means and connecting rods for operating the same, wherein the parts may be easily connected together and adjusted are of importance in 80 my folding stair, yet providing the hanger members and parts strong and of a rigid nature so as to carry the weight and strain of the 85 load of the stair.

In accordance with the patent statutes I 90 have described the principles of operation of my folding stair and hanger construction and while I have illustrated a particular formation and arrangement of the parts I desire to have it understood that these are only suggestive of a means of carrying out the principles of my invention and that changes and 95 variations may be made within the scope of the following claims without departing from the spirit of this invention.

I claim:

1. A folding stair including, sections hingedly connected together in a manner so as to fold one upon the other into a compact state. hanger means for supporting and operating said stair including, a pair of adjustable rod members which are adapted to be lengthened and shortened by rotating in either direction.

2. A folding stair including, a hanger having rod arms pivotally connected together, threaded ends formed on said rod arms of a right and left hand formation, attaching means adapted to engage said threaded ends of said rod arms whereby said rod arms may be lengthened or shortened 115 to properly position and carry the strain on said stair.

3. A folding stair including, section adapted to fold together, a hand rail extending along and connected to said stair, a 120

- spring arm adapted to support and draw on said rail to assist in raising said stair, and adjustable pivoted rod members adapted to support said stair on each side thereof.
- 5 4. A stair hanger comprising, adjustable supporting rods pivotally connected together in a manner to fold with the stair, said rods including threaded ends to permit the same to be lengthened or shortened by turning the same, a lifting means, and rods connecting said lifting means with said hanger rods.
- 10 5. A stair hanger for a folding stair comprising, side hanger rods pivotally connected together, threaded ends formed on said rods, means for engaging said threaded ends to pivotally support the same to the side of the stair and the supporting casing shoulders formed on said rods, a lifting arm adapted to connect with said rods and engage 20 against said shoulder when said arms are extended, and adjustable coil springs operating means supported in the casing adjacent said rods and adapted to engage one end of said lifting rods.
- 25 6. A hanger for a folding stair including, a hanger arm formed in two rod-like members pivotally connected together on one end, threads formed on the outer ends of said hanger, an attaching collar, a rotatable nipple carried by said collar adapted to receive said 30 threaded ends of said hanger arm, said hanger arm being adjustable by rotating the same to lengthen or shorten the distance between the supporting collars and nipples which are adapted to support the ends of 35 said hanger.
7. A hanger and lifter for a folding stair including, pairs of members pivotally connected together, threaded outer ends formed 40 on said members, a rotatable threaded nipple means adapted to engage the threaded ends of said members to permit the same to be lengthened and shortened between the supporting nipples, rigid shoulders formed 45 on some of said members, lifting rods adapted to connect with said shoulders when said members are extended, and spring and lever means adapted to engage said lifting rods to pull against said shoulders on said members to lift and fold a stair.
- 50 8. A folding stair including, a series of sections hingedly connected together in a manner to cause one section to fold against the other, a hand rail extending along one side of said 55 stair, a lifting spring adapted to support one end of said hand rail, a bracket connecting the other end to the adjacent stair section, pairs of hanger members pivotally connected together and disposed in rotatable adjusting 60 members on either side of said stair and connecting one end with a supporting casing, lifting spring members, and lifting rods connecting said spring members with said hanger members, said hand rail assisting in 65 the folding of said stair through the connecting spring thereof, and said hanger member being adapted to be operated by said lifting springs in the folding of said stair.
9. A folding stair including, stair sections adapted to be folded together, rod-like supporting and lifting members on each side of said stair, means for supporting said rods in a manner to permit the same to be lengthened and shortened by rotating the same, lifting springs for said rods, and connecting link joining said lifting springs with said rod members adapted to pull on said rod members to cause said stair sections to be folded into a compact state.
- 70 10. A folding stair including, sections adapted to fold together, hanger and lifting means comprising foldable hangers, shoulders formed on one portion of said hangers, threaded ends formed on said hangers, threaded rotatable supports for said hangers, lifting springs, and connecting links adapted to connect said springs with said rods in a manner to cause said links to engage against the fixed shoulders on said hangers to equalize the lifting pull of the springs on each side of said stair.
- 75 11. A hanger lifter for folding stair including, lifting springs, hanger arms pivotally connected together and adapted to extend on each side of said stair to connect the same with the supporting casing and form a brace for said stair, means for lengthening and shortening said hanger arms by rotating the same in their supports on the stair and casing, links connecting said hanger arms with said lifting springs, and means for engaging either of said hanger arms to hold said hanger arm steady when said stair is extended.
- 80 12. A hanger for a folding stair including, pairs of rods pivotally connected together, threaded ends on said rods, supporting members for engaging said threaded ends adapted to permit said rods to be adjusted to lengthen and shorten the same between the points of attachment of the ends by rotating said rods, said supporting means for the end of said rods being pivotally connected to permit said rods to fold with the folding of the stair, and lifting springs and arms connecting said rods to cause the stair to be lifted through said rods.
- 85 13. A folding stair including, a series of sections hingedly connected together in a manner to cause one section to fold against the other, a hand rail extending along one side of said 90 stair, a lifting spring adapted to support one end of said hand rail, a bracket connecting the other end to the adjacent stair section, pairs of hanger members pivotally connected together and disposed in rotatable adjusting 95 members on either side of said stair and connecting one end with a supporting casing, lifting spring members, and lifting rods connecting said spring members with said hanger members, said hand rail assisting in 100 the folding of said stair through the connecting spring thereof, and said hanger member being adapted to be operated by said lifting springs in the folding of said stair.
- 105 14. A hanger for a folding stair including, pairs of rods pivotally connected together, threaded ends on said rods, supporting members for engaging said threaded ends adapted to permit said rods to be adjusted to lengthen and shorten the same between the points of attachment of the ends by rotating said rods, said supporting means for the end of said rods being pivotally connected to permit said rods to fold with the folding of the stair, and lifting springs and arms connecting said rods to cause the stair to be lifted through said rods.
- 110 15. A hanger lifter for folding stair including, lifting springs, hanger arms pivotally connected together and adapted to extend on each side of said stair to connect the same with the supporting casing and form a brace for said stair, means for lengthening and shortening said hanger arms by rotating the same in their supports on the stair and casing, links connecting said hanger arms with said lifting springs, and means for engaging either of said hanger arms to hold said hanger arm steady when said stair is extended.
- 115 16. A hanger for a folding stair including, pairs of rods pivotally connected together, threaded ends on said rods, supporting members for engaging said threaded ends adapted to permit said rods to be adjusted to lengthen and shorten the same between the points of attachment of the ends by rotating said rods, said supporting means for the end of said rods being pivotally connected to permit said rods to fold with the folding of the stair, and lifting springs and arms connecting said rods to cause the stair to be lifted through said rods.
- 120 17. A folding stair including, a series of sections hingedly connected together in a manner to cause one section to fold against the other, a hand rail extending along one side of said stair, a lifting spring adapted to support one end of said hand rail, a bracket connecting the other end to the adjacent stair section, pairs of hanger members pivotally connected together and disposed in rotatable adjusting 125 members on either side of said stair and connecting one end with a supporting casing, lifting spring members, and lifting rods connecting said spring members with said hanger members, said hand rail assisting in the folding of said stair through the connecting spring thereof, and said hanger member being adapted to be operated by said lifting springs in the folding of said stair.
- 130 18. A hanger for a folding stair including, pairs of rods pivotally connected together, threaded ends on said rods, supporting members for engaging said threaded ends adapted to permit said rods to be adjusted to lengthen and shorten the same between the points of attachment of the ends by rotating said rods, said supporting means for the end of said rods being pivotally connected to permit said rods to fold with the folding of the stair, and lifting springs and arms connecting said rods to cause the stair to be lifted through said rods.
